(57) **CLAIM**

The ornamental design for an air-discharge opening for air-conditioners, as shown and described.

DESCRIPTION

FIG. 1 is a front view of an air-discharge opening for air-conditioners showing our new design:

FIG. 2 is a rear view thereof;

FIG. 3 is a right side view thereof;

FIG. 4 is a left side view thereof;

FIG. 5 is a top (plan) view thereof;

FIG. 6 is a bottom view thereof;

FIG. 7 is a perspective view thereof;

FIG. 8 is an additional perspective thereof;

FIG. 9 is a perspective thereof in a closed position; and,

FIG. 10 is an additional perspective thereof in a closed position.
